UNITED STATES PATENT OFFICE.

CHESTER W. RICE AND EDWARD W. KELLOGG, OF SCHENECTADY, NEW YORK, AS
SIGNORS TO GENERAL ELECTRIC COMPANY, A CORPORATION OF NEW YORK.

RADIO RECEIVING SYSTEM.

Application filed July 15, 1921. Serial No. 485,050.

Our present invention relates to radio receiving systems and more particularly to an improved arrangement of an antenna for receiving purposes.

5 This application is a continuation in part of our former application, Serial No. 372, 938, filed April 10, 1920.

One of the objects of our invention is to provide a receiving antenna which will be 10 an efficient means for receiving radio signals from a desired direction to the substantial exclusion of signals coming from other directions. Another object of our invention is to provide an antenna which, although it may not be tuned for the frequency of the signaling waves to be received, will be highly selective to these waves. Still another object of our invention is to provide a receiving antenna which will give 15 a more favorable stray ratio than antennæ which have previously been employed for receiving purposes.

In carrying our invention into effect we make use of a long horizontal receiving antenna which may be in the form of a conductor with ground connections at the ends, extending preferably approximately parallel to or at an acute angle to the direction of transmission of the signals to be received. 20 This antenna is so constructed that electrical waves of signal frequency travel therethrough at a velocity as nearly as possible equal to the velocity at which signaling waves in space will travel along the line. Assuming that the antenna lies parallel to the direction of travel of the signaling waves, this will be the velocity of light. If electrical waves travel through the antenna at the same velocity as that at which the signaling waves 25 travel along its length the signaling currents induced in the antenna will be very small at the end nearest the transmitting station and increase progressively along the length of the antenna becoming a maximum at the end farthest from the transmitting station.

In case the natural capacity and inductance of the antenna are not of the proper values to give the desired electrical wave velocity for the signal frequency, it is possible 30 to modify the characteristics of the antenna in such a way as to produce the desired wave velocity for the frequency in question. In some cases this desired velocity may be equal to the velocity of light while in other

cases it may differ therefrom as will be more fully set forth in our specification.

The novel features which we believe to be characteristic of our invention are set forth with particularity in the appended claims. Our invention itself, however, both as to its organization and method of operation, together with ways in which the particular objects thereof may be attained will best be understood by reference to the following description taken in connection with the accompanying drawing in which Fig. 1 illustrates diagrammatically one way in which our invention may be carried into effect. Figs. 2, 3 and 4 illustrate modified ways in which the wave velocity on a large antenna may be adjusted, and Fig. 5 shows typical curves illustrating the variations in signal strength along the length of the antenna.

Consider first a simple horizontal receiving antennæ 1, as indicated in Fig. 1, which extends from the receiving station at end 3 of the antenna towards the transmitting station 6 from which the desired signals are coming. The operation of such an antenna in receiving signals may be explained as follows: Assume that the signaling waves in space are traveling from station 6 in the direction of the antenna, then at the end 2 of the antenna a small current will be induced which will be propagated as a wave along the antenna toward the end 3. If the velocity of this small current wave in the antenna is equal to the velocity of the signaling wave in space, this current wave will grow as it approaches the end 3 by continuously absorbing small additional amounts of energy from the ether waves since the two waves are traveling along in phase with each other. From this analysis it appears that, if the constants of the antenna are such that the current wave travels at the same velocity as the ether wave, the longer the antenna the greater the current which will be received. There will of course be a maximum length beyond which nothing will be gained because of the losses in the antenna. The lower these losses are the greater will be the length of antenna which can be used to advantage. Even assuming a zero loss line a length will ultimately be reached when no further increase in signal strength will result from increased length because the waves on the antenna will finally

reach an amplitude equal to the amplitude of the ether waves, that is, reradiation will balance the received energy. This condition may be referred to as "saturation." If, however, the velocity of the current wave in the antenna is not quite the same as that of the ether wave then for a certain distance the two waves will add, but a point will finally be reached where one wave will be so far in advance of the other that the two will be in phase opposition. Interference will then occur and the current wave will decrease to zero and then a new wave will be started and built up. Under these conditions the strength of the signal which will be received if the receiving apparatus is located at the end 2 of the antenna, will be weak, and as the receiving apparatus is moved along the antenna in the direction in which the waves are moving the signal strength will gradually increase to a maximum, then decrease to a minimum, and increase again to a second maximum having approximately the same strength as the first maximum. The distance along the antenna between maximum and minimum will depend upon the difference in the velocity of the electric wave and the antenna and the ether wave surrounding it in space. If the velocities differ very little a long receiving antenna can be used to advantage, but if the velocities are considerably different there may be no advantage in using a greater length of antenna than that which will give the first maximum for the desired signal frequency.

Fig. 5 illustrates the variation in current strength in the antenna under the two different conditions of operation which we have described. In this figure the ordinates represent signal strength and the abscissæ represent distance along the antenna. Curve B shows the increase in current strength along the length of the antenna when the current wave in the antenna and the ether wave travel at the same velocity. This shows that the current increases along the length of the antenna quite rapidly at first, then more slowly due to saturation and line losses. It is assumed that the distance represented by this curve is the maximum length of antenna which can be used to advantage and this maximum length may be equal to several wave lengths. Curve C shows the variation in current strength along the length of the antenna for one case when the current wave and the ether wave travel at different velocities. Here the current increases until a maximum is reached at the point D; then decreases to a minimum at point E; increases to a second maximum at point F; and decreases again to a minimum at point G. Since these two maximum points are approximately of the same value it is apparent that for the velocity relations assumed in the curve C nothing will be gained in signal

strength by using a greater length of antenna than that represented by the distance A—D although there may be a gain in stray ratio due to the sharper directivity of an antenna which exceeds this length. Curve H represents the variation in current strength along the length of the antenna for another case in which the current wave and the ether wave travel at different velocities. Here the maximum current is reached at the point I and the minimum point is reached at the end of the antenna. Many of the long antennæ hitherto used, employed rubber covered wire, buried, submerged in water, or on the surface of the ground. These types of construction give low velocity and high attenuation, both of which effects limit the length of antenna which can be advantageously employed, optimum length of about one-eighth of a wave length (of the ether waves) having been observed in tests. The conditions necessary in order to secure the benefits of longer antennæ are high velocity and low attenuation.

For signaling waves traveling in the opposite direction, the currents will build up in the same manner. If these are reflected at the end 2, Fig. 1, they will return to 3 and affect the receiving apparatus, giving the antenna bi-directional properties. Reflection may be avoided by grounding the end 2 through a non-inductive resistance of a value equal to or approximating the surge impedance of the antenna; which is

$\sqrt{\frac{L}{C}}$ where L and C are the inductance and capacity of the antenna per unit length. By adopting this or any other expedient which eliminates reflection from the far end the antenna will be given marked unidirectional properties and will be highly selective for signals coming from one direction to the exclusion, not only of signals coming from other directions but to static impulses coming from other directions as well. The greater the length of the antenna compared with the signal wave length, the more sharply directional the antenna will become.

The damping resistance 5 in Fig. 1 might be replaced by a receiving set having an equivalent impedance without impairing the usefulness or unidirectional property of the antenna when used with the receiving circuit 4. If the receiving circuit 4 also has an impedance approximately equal to the surge impedance of the antenna, then a receiving circuit located at the end 2 will receive only signals coming in the direction 3—2, or opposite to those received by the receiving circuit 4. A long antenna may thus serve two receiving stations, for signals coming from opposite directions and there will be no loss of efficiency by thus making the antenna serve a double purpose. In fact, for maxi-

mum efficiency the receiving circuits should be designed to have an effective impedance equal to the antenna surge impedance.

In accordance with theoretical considerations, if an antenna were to be freely suspended and if the surface of the earth constituted a perfectly conducting parallel plane, current waves would travel through the antenna conductor at a velocity equal to the velocity of light. In practice, this theoretical condition may be difficult to obtain because of ground resistance and because of the necessity for providing supports for the antenna.

The effect of these supports may be to add shunt capacity to the line without causing any compensating change in the other line constants. The effect of the excess shunt capacity may be neutralized for continuous waves of a particular frequency, by means of shunt inductances connected at frequent intervals between the antenna and ground. Or the effect of excess shunt capacity in slowing down the rate of wave propagation may be compensated for by the insertion of condensers in series with the line conductors, thereby neutralizing part of the series inductance and increasing the wave velocity. Such shunt inductances or series condensers should be sufficiently close together (in no case more than $\frac{1}{\pi}$ wave length apart) to give substantially the effect of distributed shunt inductance or series capacity for the frequency which is to be received.

By choosing proper values for the inductances and condensers the wave velocity on the line for continuous waves of any specified frequency may be made equal to or greater than the velocity of light. If the line has been adjusted to give a velocity of wave propagation equal to the velocity of light for a specific frequency, then for continuous sinusoidal waves the apparent velocity of propagation will be greater than the velocity of light for lower frequencies than that for which the line is adjusted, and will be less than the velocity of light for signals of a higher frequency than that for which it is adjusted.

An alternative method of correcting wave velocity on a long antenna consists in the introduction at suitable intervals of links of artificial line, which will act in such a way as to retard or advance the phase of the wave. Thus the introduction of a link consisting of series condensers and shunt inductances will have the effect of advancing the phase or increasing the average wave velocity for the antenna as a whole, while the introduction of links consisting of series inductances 9 and shunt condensers 10, as shown in Fig. 3, will produce a delay or slow down the average wave velocity of the antenna. For continuous waves the intro-

duction of a delay link slightly less than one wave length long will by retarding the phase of the wave by something less than one cycle, have an effect equivalent to advancing the phase or increasing the wave velocity, while for single impulses or highly damped waves the effect would be to break up the resulting disturbance on the antenna into several relatively feeble impulses.

Artificial lines or links of the kind just described may be introduced without causing serious reflection losses in the antenna, either by making the links alike and spaced sufficiently close together, provided the links themselves are short, or by designing the artificial lines so that their surge impedance is equal to the surge impedance of the unadjusted antenna.

The above described methods of adjusting velocity give different velocities for different frequencies. This permits of selectivity based on frequency, in addition to the selectivity offered by reason of the directive properties of the antenna. For example, referring to the curves of Fig. 5 an interfering sending station might be located in a direct line with the transmitting station whose signals it is desired to receive. Assuming that the wave length of the signal transmitted from this interfering station differs from that of the desired signals for which the antenna is adjusted, the velocity of its waves on the antenna can be made to differ from their velocity in space by such an amount that a node, such as shown at points E or G, of curve C, Fig. 5, will occur at the point where the receiving apparatus is located.

If such is the case the interfering station will produce substantially no effect upon the receiving apparatus. Under other conditions, supposing two currents in the antenna from two stations in line with each other to be represented by the curves C and H, Fig. 5, reception could be accomplished from the station represented by the curve H by locating the receiving apparatus at the point I where this current is large and the current of curve C is substantially a minimum.

If the natural capacity and inductance of the antenna have substantially the values required to give a velocity of wave propagation in the antenna equal to the velocity of light such an antenna would have the same wave velocity for all frequencies and while possessing the desired directive properties would not be selective for frequency. Under these circumstances it may be desirable to insert series inductances 7, Fig. 1, which of themselves would lower the wave velocity on the antenna, and to neutralize the effect of these inductances for a particular frequency, by inserting series condensers 8.

It may also be desirable in some cases in

- order to further sharpen the frequency selectivity of the line, to use added shunt capacity 11, as a means of slowing down the wave velocity and to neutralize this by shunt inductances 12 as indicated in Fig. 2. These added conductors connecting the antenna with ground may serve a further useful function in assisting the collection of energy from the signal wave in space. 10 In the case of a line loaded in this manner the antenna will act purely as a transmission line at the desired frequency while for all frequencies below that the line becomes analogous to a high pass filter or lumped artificial line consisting of series condensers and shunt inductances, and for all frequencies above signaling frequency the line becomes analogous in its action to a low pass filter, or lumped artificial line consisting of 20 series inductances and shunt condensers. The filter action of the adjusted antenna offers a means of eliminating undesired signals or disturbances having a wave length differing from that of the desired signal. 25 This feature is under control by properly proportioning and spacing the inductances and condensers, in accordance with well established principles. An equivalent action may be obtained by using a filter in the receiving station.

Another interesting property of this type of antenna is its effect in stray elimination. Consider an antenna of this type which was normally slow, for example, a rubber covered wire or iron wire, but which is speeded up by series condensers for a particular frequency. For static impulses of steep wave front the series condensers will act practically as zero impedance and the static will be propagated along the line at its normal low velocity. Similarly, if shunt inductances were used for speeding up, these would act as infinite impedance for static impulses and the static wave would be propagated at the low normal velocity of the line. This means that the static current in the antenna will alternately build up and then build down by interference with the static wave in the ether and if there happens to be a certain particularly effective frequency in the static which is troublesome in exciting the receiver tuning circuit it is possible to locate the receiving apparatus at an interference node for static. The signal bearing a continuous wave will progressively build up to a large value at the point selected for the receiving apparatus.

It is not necessary for good results that an antenna of the type we have been describing be placed parallel to the direction of travel of the waves to be received although approximate parallelism may normally be desirable. If the direction of travel of the waves in space makes an angle θ with the antenna, then the point of intersection of a

wave front with the antenna (i. e. the point of maximum instantaneous induced potential on the antenna) will move along the antenna with a velocity

$$\frac{C}{\cos \theta}$$

70

in which C is the velocity of light, and in order for such a wave to produce the maximum effect in the receiving apparatus, the 75 velocity of propagation on the antenna should be

$$\frac{C}{\cos \theta}$$

80

Thus by producing an effective wave velocity on the antenna somewhat greater than the velocity of light, the antenna can be made to show its maximum sensitiveness for waves coming from an angle.

Since the form of the current distribution curve C or H, Fig. 5, depends upon the difference between the velocity of waves on the antenna and the velocity with which an ether disturbance travels along the antenna, 90 which is

$$\frac{C}{\cos \theta'}$$

85

there are certain values of the angle θ which for any given antenna will give zero current at the receiving end. These dead points or directions from which a signal cannot be heard, depend on the wave length, the length of the antenna and the antenna wave velocity. This affords means of eliminating interference from a sending station, either by adjusting the length of the antenna or by adjusting its constants and thereby its wave velocity so that signals of that wave length and coming from that direction will be inaudible.

95

The adjustment of wave velocity on an antenna can be made in such a way as to give not only a desired velocity for one frequency, 110 but at the same time to give a desired velocity for a second frequency. For example, suppose that the antenna points directly toward one transmitting station whose signals are to be received and that a second transmitting station of greater wave length lies at an angle θ with the direction of the receiving antenna. For signals from the first station the wave velocity on the antenna should be that of light, while to obtain maximum intensity for signals from the second station the velocity should be

$$\frac{C}{\cos \theta}$$

115

where C stands for the velocity of light. If an antenna is employed whose natural constants are such as to give a wave velocity C, no adjustment would be necessary for the first station but the wave velocity would be 130

too low for strongest reception of signals from the second station. If now series inductances are introduced, and their reactance neutralized by series condensers for the frequency of the signals from the first station, the wave velocity for these signals will be unchanged, but the velocity will be increased for the longer waves of the second station. The larger the values of inductance and capacity the greater will be the velocity for the longer waves. Hence values of inductance and capacity can be chosen which will give the desired velocity

$$15 \quad \frac{C}{\cos \theta}$$

for signals from the second station, while leaving the velocity for waves from the first station unchanged.

20 A similar result may be obtained for two or more signaling waves differing sufficiently in frequency coming from the same direction or different directions by an arrangement such as that shown in Fig. 4. Series inductances 13 and series condensers 14 may be proportioned to give the desired velocity for one wave and series inductance 15 and series condensers 16 may be proportioned to give the desired velocity for another wave. The 30 wave velocity on the antenna for waves of a different frequency than those desired may then be such that a point along the length of the antenna may be selected which will be a node for interfering waves.

35 An antenna having a velocity less than that of light may show sharper directivity than an antenna of the same length having full velocity, because while there is a loss of signal intensity as a result of the low velocity on the antenna, the effects of disturbances coming from other directions may be reduced in still greater proportion. If the construction of the antenna line is such as to give a velocity nearly equal to that of light, improved directive properties will under some circumstances result from slowing down the line by loading it either with capacity to ground or with series inductance.

40 What we claim as new and desire to secure by Letters Patent of the United States, is:—

55 1. A receiving system for radio signals comprising a substantially horizontal antenna extending in a direction at an angle to the general direction of transmission of the waves to be received and having a length at least substantially as great as the wave length of the signals to be received, said antenna being so constructed and its constants so adjusted that electric waves induced therein will be propagated along its length at a velocity substantially equal to the velocity at which the desired signaling waves travel along its length in the ether.

60 2. A receiving system for radio signals

comprising a substantially horizontal antenna extending in a direction at an angle to the general direction of transmission of one set of waves to be received and having a length at least substantially as great as the 70 wave length of the signals to be received, said antenna being so constructed and its constants so adjusted that electric waves induced therein by signaling waves coming from more than one direction will be propagated along its length at velocities substantially equal to the velocities at which the corresponding desired signaling waves travel along its length in the ether.

3. A receiving system for radio signals 80 comprising a horizontal antenna having a length at least substantially as great as the wave length of the signals to be received and having such natural constants that current waves will be propagated therein at a velocity substantially equal to the velocity of light and means for reducing the velocity of propagation of current waves therein in order to obtain improved directive properties.

4. A receiving system for radio signals comprising a horizontal antenna having inserted therein at intervals along its length parallel sets of series inductances and capacities, each set of series inductances and capacities being so proportioned that current waves of one particular frequency will be propagated along the length of the antenna at a velocity substantially equal to the velocity of light.

5. A receiving system for radio signals comprising a horizontal antenna having inserted therein at intervals along its length parallel sets of series inductances and capacities, each set of series inductances and capacities, being so proportioned that current waves of one particular frequency will be propagated along the length of the antenna at a velocity substantially equal to the velocity at which the corresponding signaling 100 wave travels along its length in the ether.

6. A receiving system for radio signals comprising a substantially horizontal antenna having a length at least substantially as great as the wave length of the signals to be received and said antenna being so constructed and adjusted that electric waves induced therein by signaling waves coming from different directions at least one of which is different from the direction in 115 which the antenna extends will be propagated along its length at velocities substantially equal to the velocities at which the corresponding signaling waves travel along its length in the ether.

120 In witness whereof, we have hereunto set our hands this 14th day of July, 1921.
